HARVEY D. HARADEN, OF HARTFORD, VERMONT.

Assign to himself & C. W. Haraden.
Letters Patent No. 77,977, dated May 19, 1868.

IMPROVEMENT IN HUBS FOR CARRIAGE-WHEELS.

The Schedule referred to in these Letters Patent and making part of the same.

TO ALL PERSONS TO WHOM THESE PRESENTS MAY COME:

Be it known that I, HARVEY D. HARADEN, of Hartford, in the county of Windsor, and State of Vermont, have invented a new and useful Improvement in the Hubs of Carriage-Wheels; and I do hereby declare the same to be fully described in the following specification, and represented in the accompanying drawings, of which—

Figure 1 is a top view,

Figure 2 a longitudinal section, and

Figure 3 a transverse section of a wheel-hub constructed in accordance with my invention, and as ready for the reception of the sleeve or box of an axle.

The hub, as shown in the drawings, is composed of a middle part, A, of cast metal, and two portions, B B, of wood, the latter being secured in sockets formed in the part A.

The said part A is composed of two flat and parallel and perforated disks, *a a*, united by a series of radial connections, *b b b*, arranged at equal distances apart, and in manner, with respect to the disks, as shown in the drawings.

From the outer face of each disk a ring, *c*, projects concentrically with the disk, so as to form on the side of the disk a socket, *d*, to receive one of the end parts, B, which is turned so as to enter and fit closely to such socket, and may be secured thereto by means of screws, *f*, going through the ring and screwed to the wood.

The spaces *g g* between the two annuli and their radial connections, are designed to receive the tenons of the spokes, which may be made in breadth and width nearly if not quite equal to the base portions of the spokes.

The above mode of making a hub ready for reception of the sleeve, renders the hub very strong, and not only prevents the wooden parts from splitting, but supports the spokes to great advantage. It is far preferable to a hub made either wholly of metal or wholly of wood, which I do not claim.

I am aware of the inventions described in the United States Patents, Nos. 65,257 and 74,117, which represent an open frame of metal, composed of two annuli arranged parallel to each other, at a short distance apart, and connected by metallic bars extending from one to another; the whole being to be driven on a wooden cylinder or hub, and to receive and hold a series of spokes tenoned into such cylinder.

My invention differs from this hub and spoke-supporter, inasmuch as, instead of two rings, I employ two disks connected by bars, and having a cylindrical socket on the outer face of each disk, the sockets being to hold two separate cylinders or pieces, B B, of wood, which are to receive an axle-box.

With my invention the spokes are wholly supported by the metallic disks, and are not tenoned into a wooden cylinder. The disks at their centres are to be bored to receive the axle-box, and they serve, with the wood portions B B, to sustain it.

Furthermore, the disks, by extending across each of the socket-rings, form shoulders to support the ends of the pieces B B. With my improvement, the spokes are entirely insulated from the wood for sustaining the axle-box, and thus, while the wheel may be in use, they cannot operate in any way to loosen the connection of the parts A B B, by which the box is supported.

I therefore make no claim to the invention described in either of such patents.

I claim the improved supporter, A, or arrangement of disks, socket-rings, and radial connections, as set forth.

Also, the combination and arrangement of the two separate cylinders or pieces of wood, B B, with the disks, the socket-rings, and these radial connections, arranged together and cast in one piece, as set forth.

HARVEY D. HARADEN.
